UNITED STATES PATENT OFFICE.

WILLIAM L. GROOM, OF COAL VALLEY, ALABAMA.

COMBINED MINING AND TRACK TOOL.

No. 911,038.

Specification of Letters Patent.

Patented Feb. 2, 1909.

Application filed October 5, 1907. Serial No. 396,040.

To all whom it may concern:

Be it known that I, WILLIAM L. GROOM, a citizen of the United States, residing at Coal Valley, in the county of Walker and State 5 of Alabama, have invented an Improvement in a Combined Mining and Track Tool.

This invention relates to a combined mining and track tool, and particularly to a tool or pick, which comprises a peculiarly-constructed head which head is provided with means for receiving and securing thereto tools to be used for different purposes.

An object of the invention is the improvement of the construction of a tool or pick, which comprises a minimum number of parts, is comparatively simple in structure, and very efficient in operation.

With this and other objects in view, the 20 invention consists of certain novel constructions, combinations, and arrangements of parts, as will be hereinafter fully described and claimed.

In the drawings: Figure 1 is a view in side 25 elevation, partly in section, of a tool or pick constructed in accordance with the present invention. Figs. 2 and 3 are views similar to Fig. 1, showing the different kinds of tools secured to the head of the tool or pick. Fig. 4 is a sectional view taken on line 4, 4, 30 Fig. 1. Fig. 5 is a view, in side elevation, of the pick or tool as it appears in operation.

Referring to the drawings by numerals, 35 1 designates the body of the head, which is provided with ends 2, and with a handle-receiving portion 3.

Each end 2 is provided with preferably, 40 a square socket 4; a set-screw 5 is threaded into each end, and is adapted to have its inner end extend into the socket 4.

The head is provided on the side opposite to the handle-receiving portion 3, or, in other words, upon its outer face, with an outwardly-bulged or curved reinforcing 45 guard 6, which is integrally connected at its ends to the end portions 2 of the body, and the guard 6 is provided with an enlarged, central opening or aperture 7 for facilitating the insertion of the handle 8 into the head; 50 the handle 8 being normally positioned in the longitudinally-extending opening or aperture 9, which extends through the body of the head. After the handle 8 has been placed in the opening or aperture 9, a suitable wedge or fastening member 10, Fig. 4, 55 may be driven into the inner end of the han-

dle through aperture 7, of the outwardly-curved or bulged guard or flange 6 for securing the handle in position.

The outwardly-curved or bulged guard or 60 flange 6 increases the strength of the pick-head, although it decreases the amount of material used in the construction thereof; it will be seen that there is left an elongated slot or opening 11 between the body of the 65 head and the guard or flange 6; furthermore, as seen in Fig. 5, when the pick is in use, and it is desired to pry up a load, the outwardly-bulged guard or flange 6 will facilitate this operation, as it acts as a fulcrum or bearing 70 point for assisting the detachable points 12 in raising or moving the load, which may be a piece of ore or coal or a tie, as indicated, as at 13.

The pick-points 12 are detachably set 75 secured in the sockets 4 by means of the set-screws 5 and can be quickly detached, when it is desired to substitute therefor a different kind of a tool.

To minimize the cost of construction of 80 the pick-head, the portion 3 is comparatively thin, although it is greatly reinforced by having the portions 14 of the body extend inward, producing a V-shaped reinforcing rib 15 upon each side of the body, 85 thereby materially strengthening the body and also preventing the portion 3 from being easily broken, for the reason that if the side of the head comes in contact with a foreign object, the object will strike against a rib 15 90 and prevent the object from hitting the thin or reduced portion of the head. Therefore, it is to be noted that by reason of my peculiarly-constructed reinforcing ribs 15 and the outwardly-bulged flange or portion 6, I 95 have provided a very light head that is durable and efficient in operation.

In Fig. 2, I have shown a hammer 16, provided with a squared shank 17; the shank 17 being positioned in one of the sockets 4 and 100 engaged by set-screw 5. In the opposite socket 4 of the head, is positioned a squared shank 18 of an adz, which adz is provided with a curved blade 19 terminating in a body portion 20, which body portion is provided 105 with a primary shoulder 21 and an auxiliary shoulder 22; the shoulders bearing against the outer, flat face of the end of the head in which the shank 18 is positioned, and it is to be noted that the shoulder 21 is longer than 110 shoulder 22, whereby a more secure fastening or strengthening device is produced, for

the strain is often greater upon the shoulder 22, as the blade 19 engages an object.

In Fig. 3, I have shown a hatchet, secured to one of the ends 2, and said hatchet comprises a blade 23 and a shank 24; the shank being positioned in the socket and secured by means of a set-screw 5.

The aperture or opening 7 in the outwardly-bulged guard is, preferably, larger 10 than the aperture 9, for facilitating the position of the handle in the head, but said aperture does not materially weaken the guard, for the guard can be formed as thick as desired, beside the lever function of the guard

15 will be performed when the tool is in use.

The operator can carry a number of different kinds of tools in his pocket, and can quickly detach one of the tools from the head and substitute therefor a different kind of 20 tool or tools, and, occasionally, obviating the necessity of carrying a number of tools or pick-heads, for one head will do for all of the detachable tools, and, consequently, minimizing the weight to be conveyed by 25 the operator or miner, beside minimizing the cost of the outfit, for one handle and head will answer, for a number of purposes or uses, by merely changing the tools when desired.

It is to be noted that each rib 15 comprises 30 a pair of portions integrally connected at their inner ends, and the portions of each rib taper from their inner ends to their outer ends.

What I claim is:

1. In a device of the character described, 35 the combination of a head comprising a body provided upon opposite sides with V-shaped reinforcing ribs and with sockets formed in its ends, set-screws threaded into the ends and adapted to extend at one end into the 40 sockets, said body provided upon its outer face with an integral, outwardly-curved or bulged guard spaced from the body intermediate its ends, and said body and guard provided with registering openings or aper- 45 tures, the aperture in said body adapted to receive a handle.

2. In a device of the character described, the combination with a handle, of a head positioned upon said handle, said head comprising a body, said body provided with reinforcing ribs at opposite sides and with an outwardly-bulged guard upon one face, the guard integral at its ends with the body and spaced therefrom intermediate its ends. 50

3. In a device of the character described, the combination of a head provided at its ends with tool-receiving sockets or pockets and upon one side intermediate its ends with an outwardly-curved or bulged guard, the 55 guard being spaced intermediate its ends away from the body.

WILLIAM L. GROOM.
